US0D1074720S

(12) United States Design Patent (10) Patent No.: US D1,074,720 S
(45) Date of Patent: * May 13, 2025

(54) DISPLAY SCREEN WITH GRAPHICAL USER INTERFACE

(71) Applicant: IGT, Las Vegas, NV (US)

(72) Inventors: Stephanie Quiles, Las Vegas, NV (US);
Derick Rougeau, Sparks, NV (US);
Steve Richardson, Round Rock, TX
(US)

(73) Assignee: IGT, Las Vegas, NV (US)

() Term: 15 Years

(21) Appl. No.: 29/963,231

(22) Filed: Sep. 16, 2024

Related U.S. Application Data

(62) Division of application No. 29/809,890, filed on Sep. 30, 2021.
